UNITED STATES PATENT OFFICE.

MAX L. SCHLUETER, OF CHICAGO, ILLINOIS.

FLOOR-SURFACING MACHINE.

1,219,670.

Specification of Letters Patent. Patented Mar. 20, 1917.

Application filed June 16, 1913. Serial No. 773,811.

To all whom it may concern:

Be it known that I, MAX L. SCHLUETER, a citizen of the United States, residing in Chicago, in the county of Cook and State of Illinois, have invented a new and useful Improvement in Floor-Surfacing Machines, of which the following is a specification.

This invention relates to improvements in floor surfacing machines and is in the nature 10 of an improvement on the surfacing machine described in Patent No. 882,847, issued to me March 21, 1907.

Objects of the invention are to provide a surfacing machine which is adapted to treat 15 floor surfaces completely and directly up to the walls around the edges of the floor and to so arrange the surfacing rollers and the motors for driving the same as to occupy as small a space as possible.

20 Other objects of the invention are to provide an edge surfacing roller which may be readily removed and interchanged for others; to provide a caster wheel yieldingly and adjustably supported relatively to the 25 guiding handle of the machine; and to provide means for holding the surfacing roller clear from the floor when the edge roller is being interchanged or other parts are being adjusted or repaired.

30 The invention further consists in the improvements in the parts and devices, and in the novel combinations of the parts and devices as herein shown, described or claimed.

In the drawing forming a part of this 35 specification, Figure 1 is a side elevation of a surfacing machine embodying my improvements; Fig. 2 is a top or plan view of the structure illustrated in Fig. 1; Fig. 3 is a transverse vertical section through the 40 main surfacing roller and immediate parts and showing edge surfacing roller in elevation; and Fig. 4 is a broken longitudinal sectional view taken substantially on the line 4-4 of Fig. 3.

45 In said drawing 10 designates the frame of the machine to which are detachably secured side plates 11, provided with journal bearing guides 12, the latter having slidably mounted therein bearings 13 adjustably and 50 yieldingly supported by springs 14 and adjusting rods 15. Mounted in the bearings 13 is a transversely extending sleeve 16 the latter having secured thereto at one end, a sprocket gear 17 by which said sleeve is 55 driven, the sprocket gear 17 being rotated

by means of a sprocket chain 18 which takes over and is driven by a sprocket gear 19 mounted on one end of the armature shaft of any suitable form of motor 20, the latter being supported on the frame 10 and located substantially directly above supporting wheels 21 on which the frame 10 is mounted, the wheels 21 adapting the machine to be easily moved back and forth over a floor as will be understood.

Secured to the sleeve 16 and located between the side plates 11, is a main surfacing roller 22, the surface of said roller being provided with sand-paper or other material suitable for treating the floor. Extending 70 entirely through said sleeve 16 is a shaft 23, the latter being held in place in the sleeve 16 and prevented from rotation relatively thereto by a pin 24 engaging in a slot 25 on the end of the sleeve 16, the pin being held in the slot by a nut 26 threaded on the opposite end of the shaft 23 and engaging the end of the sleeve 16. On the end of the shaft 23, located on the opposite side of the 75 machine to that on which the driving mechanism is located, is mounted an edge or supplemental surfacing roller 27 which, as clearly shown in the drawing, is entirely clear of the frame of the machine and all of its parts, thereby adapting the machine to 80 treat the edges of floors directly up to the walls.

The surfacing rollers and frame are yieldingly supported in front of the wheels 21 by 85 caster wheels 28, these caster wheels being so arranged that when no downward force is exerted on the surfacing rollers the latter will be held approximately one-half inch above the floor. The machine is provided with the usual dust collecting pipe 29 and 90 fan 30, the latter being driven from the motor 20 through the belt 31. Secured to the top of the motor or to any other suitable part of the frame and extending rearwardly 95 is a guiding handle 32, the latter also carrying a switch 33 for governing the motor, said switch being represented conventionally in the drawings. Secured to the under side of the handle 32 is a bracket 34 in which is slidably mounted a sleeve 35, the latter having an upwardly extending rod 36 provided with a pin 37 which cooperates with a rack 38 secured on the handle whereby the sleeve 35 may be adjusted relatively thereto, 100 said sleeve being normally urged upward by 110

a spring 39. Slidably connected with the sleeve 35 is a rod 40, in the forked lower end of which is mounted a rear caster wheel 41, the wheel 41 and rod 40 being cushioned 5 with respect to the sleeve 35 by means of the spring 42. The rod 40 is provided with a small foot tread 43 whereby the operator may hold the wheel 41 down while lifting the handle 32. At the front of the machine 10 is provided a bolt or other suitable device 44 by which the surfacing rollers may be held relatively high above the floor when the edge surfacing roller is being interchanged or the machine otherwise repaired.

15 From the preceding description, it will be seen that by mounting the motor directly over the supporting wheels 21, the machine is made more compact than the construction described in my said patent and furthermore 20 the weight is brought more directly over the surfacing rollers, and by mounting the rear caster wheel 41 yieldingly and adjustably relatively to the handle 32 I am enabled to vary the pressure exerted upon the surfacing 25 rollers, at the same time allowing the machine to accommodate itself to any unusual unevenness in the floor and also relieving the operator from the necessity of holding up the handle 32 to maintain the 30 pressure on the surfacing rollers.

Although I have herein shown and described what I now consider the preferred embodiment of my improvements, yet it will be understood that various changes and 35 modifications may be made in the parts and arrangements of the parts without departing from the spirit of the invention, and all such changes and modifications as contemplated to come within the scope of the 40 claims appended hereto.

As shown in dotted lines in Fig. 3, the edge surfacing roller is adapted to be placed on the opposite side of the machine to that shown in full in said figure, thereby adapting 45 the machine to treat all edge portions of a floor directly up to the corners of a room.

I claim:—

1. A floor surfacing machine, including in combination: a frame; a main surfacing 50 roller carried by said frame and mounted in adjustable, yieldable bearings; an edge surfacing roller carried by said frame and located outside thereof to thereby adapt the machine for treating the edge portions of 55 floors directly up to the walls; and means

for rotating said rollers, substantially as specified.

2. A floor surfacing machine, including in combination: a frame mounted on supporting wheels; a surfacing roller carried by said 60 frame and located in front of said wheels; a motor mounted on said frame and located substantially directly above the supporting wheels to thereby minimize the length of the machine and to bring the weight over 65 the surfacing roller; front caster wheels yieldably connected with said frame; a handle extended rearwardly from the machine; and a rear caster wheel adjustably connected to said handle to thereby regulate the pressure placed upon the surfacing roller, substantially as specified. 70

3. A floor surfacing machine, including in combination: a frame mounted on supporting wheels; a surfacing roller carried by said 75 frame and located in front of the supporting wheels; means for operating said roller; front and rear caster wheels yieldingly connected to said frame, the rear caster wheel being also vertically adjustable to thereby 80 regulate the pressure placed upon the surfacing roller, substantially as specified.

4. A floor surfacing machine, including in combination, a frame adapted to be moved over the floor, an edge surfacing roller 85 carried by said frame and located at one side thereof, said edge roller being detachably mounted on the frame and adapted to be placed on either side thereof and thereby adapt the machine to treat the edge portion 90 of floors in the corners, means for rotating said roller mounted above said roller and supported in part thereby, and means for regularly varying the amount of weight supported by said roller when in operative position, substantially as specified. 95

5. A floor surfacing machine including, in combination, a frame having a pair of wheels arranged upon a transverse axle, a surfacing roller in front of said axle, and 100 power mechanism located directly above said axle, said frame being tiltable forwardly to cause part of the weight of said power mechanism to be borne directly by said roller, substantially as specified.

MAX L. SCHLUETER.
